(57) **CLAIM**

The ornamental design for a framing member, as shown and described.

DESCRIPTION

FIG. 1 is a front perspective view of a framing member, showing our new design;

FIG. 2 is an end view of the framing member of FIG. 1;

FIG. 3 is a detailed end view of the designated portion of the framing member shown in FIG. 2;

FIG. 4 is a detailed top view of an embossment of the framing member of FIG. 1; and,

FIG. 5 is a side cross-sectional view of the embossment of FIG. 4 taken along line 5-5 thereof.

The broken lines in FIGS. 1-2 are included for purposes of illustrating portions of the framing member that form no part of the claimed design. The breaks and brackets in some views indicate, for ease of illustration, that the precise width and length of the framing member are not claimed.
